United States Patent Office.

AZRO HEALY, OF KALAMAZOO, MICHIGAN.

Letters Patent No. 65,569, dated June 11, 1867.

IMPROVEMENT IN LIFTING-JACK.

The Schedule referred to in these Letters Patent and making part of the same.

TO ALL WHOM IT MAY CONCERN:

Be it known that I, AZRO HEALY, of the village and county of Kalamazoo, in the State of Michigan, have invented a new and useful improvement on "Lifting-Jacks;" and I do hereby declare that the following is a full, clear, and exact description of the construction and operation of the same, reference being had to the annexed drawing, forming a part of this specification, in which a perspective view of my said invention is given.

The nature and object of my invention is to furnish such ready facility for adjustments of the lifting-bar from a fixed operating point as to permit the use conveniently of a simple and inexpensive yet powerful arrangement of levers for the lifting of heavy bodies, especially when in situations not easily accessible; and the better to enable others skilled in this branch of mechanical art to construct this my said invention I will now proceed to describe it.

The frame of my improved jack is usually made of wood, and consists of a plank bed, A, and rail, B, to which two posts, C and D, are framed. The post C is made higher than the other to receive the head of the prime lever, L, and instead of making each post in one solid single piece, and cutting away for the reception of the various parts, to be hereinafter described, I find it more convenient, and usually construct each one of two separate pieces framed a proper distance apart, as seen in the drawing. The lifting end of the lever L (which is curved) is jointed between the high posts by a stout fulcrum-pin, a, and a strong lifting-chain, M, is secured behind the fulcrum, and passes downwards and is connected to the free end of a second lever, N, which is jointed at O to the short posts. The length of chain can be varied in linking to the hook j. A section of post is represented as broken away, to exhibit the foot-pawl P¹ engaging with the teeth of a ratchet segment, R, with which the lifting end of the lever N is provided, to sustain the load. The pawl may be kept in contact with the ratchet by a spring, s, or so constructed as to operate by its own gravity. E represents what usually constitutes the lifting-bar, to be applied directly under the object to be raised. It is connected by a pin, p, or otherwise, to the lever below, and passes freely through a mortise in the rail B above. But in order to facilitate its adaptation to objects at varying heights, and for ready readjustments in lifting by successive strokes of the lever, I employ, in connection with the bar E, a longer bar, F, (usually of iron,) provided with a head, G, to be applied underneath the object, and the bar is furnished with ratchet teeth, as may be clearly seen, on its front face, which teeth engage with a lifting-pawl, P², hinged somewhere central to the bar E, which is furnished with socket bands, S, within which the ratchet lifting-bar, when not engaged with the pawl, may slide freely up and down. A wire string or chain, e, is connected to the bar above the toothed portion, and passes through an opening in the rail and over a small sheave, h, thence between the posts through a lining piece, i, where it is furnished with a ring or other handle within easy reach of the operator at the lever, to bring the adjustable bar F as close as possible to the object to be lifted, and a wire, f, below, passing similarly between the posts, connects with the lifting-pawl P² to detach it in order to permit the said bar to descend when necessary. Instead of hinging one of the ends of the lever N at one permanent point, O, a series of holes for vertical adjustment may be made, or a ratchet and pawl, in connection with steadyng-guides or stops, may be employed to elevate that end alternately with the other.

I do not deem it necessary to give a detailed description of the various manipulations and adjustments which may be required in lifting heavy bodies by my jack under all possible conditions. For lifting and holding anything from the ground temporarily, say a loaded wagon-axle for lubrication, the operator, after properly placing the lifting-bar underneath, brings it up first as nearly as practicable in contact, by pulling at the cord e, when the pawl P² will drop into the nearest notch and lock the two bars together. Then depressing the lever L, he lifts, by means of the connecting-chain, the second lever N, and with it the combined lifting-bars and wagon. The pawl engaging in the end ratchet, supports the load as long as necessary. In lowering back, the operator can throw his whole force on the lever for a short lift to relieve the pawl, then placing one foot on the end of the horizontal arm at x and pressing down, he keeps the said pawl disengaged until the load is carefully lowered. When the load cannot be raised a sufficient height by one stroke of the levers, blocking is interposed, when the combined bars are lowered as before, and the ratchet-bar brought up by its cord for a succeeding lift. Should the scope of the ratchet-bar F not prove sufficient, the bar can be lowered by detaching the pawl; and by blocking up the jack itself, as usual, the lifting is renewed.

I do not claim by itself the combined arrangement of the levers and hoisting chain, for that is old; but what I claim as new, and desire to secure by Letters Patent, is—

1. The arrangement and combination of the prime lever L, lifting chain M, and secondary lever N, with the end ratchet R, and foot-pawl P¹, substantially as and for the uses herein set forth.

2. I claim the aforesaid arrangement of combined parts used in connection and combination with the lifting-bars E and F, lifting-pawl P², and manipulating cords or wires e and f, the several parts being arranged relatively with the frame of the jack, and with each other, and constructed and operated substantially in the manner and for the purposes herein described.

AZRO HEALY.
